UNITED STATES PATENT OFFICE

TELESPHORE BABIN, OF HOUMA, LOUISIANA

SAFETY HEATER

Application filed October 16, 1931. Serial No. 569,298.

This invention relates to stoves or heaters especially adapted for burning wood and like fuels and has for the primary object, the provision of a device of the above stated character which may be manufactured and shipped or transported in a knocked down position and may be easily assembled when desired and when in use will provide maximum heat from a minimum amount of fuel 10 with a maximum amount of safety.

Another object of this invention is the provision of a novel draft or damper capable of furnishing maximum draft to the fire when desired and which will not be affected 15 by the accumulation of ashes within the fire box.

A further object of this invention is the provision of a stove of the above described character which will be simple, durable and 20 efficient and which may be manufactured and sold at a comparatively low cost.

With these and other objects in view, this invention consists in certain novel features of construction, combination and arrangement of parts to be hereinafter more fully described and claimed.

For a complete understanding of my invention, reference is to be had to the following description and accompanying drawings, 30 in which

Figure 1 is a side elevation illustrating a stove or heater constructed in accordance with my invention.

Figure 2 is a top plan view illustrating the 35 same.

Figure 3 is a bottom plan view illustrating the base.

Figure 4 is a vertical sectional view illustrating the damper or draft associated with 40 the fire box.

Figure 5 is a detail sectional view illustrating the damper or draft regulator.

Figure 6 is a fragmentary perspective view illustrating a portion of the base.

Figure 7 is a sectional view taken on the line 7-7 of Figure 4.

Referring in detail to the drawings, the numeral 1 indicates a fire box or drum constructed of sheet metal or any other material 50 suitable for the purpose and is of cylindrical

formation with its ends fully opened. The fire box or drum is constructed from a single length of material which is bent into cylindrical formation and has its abutting edges curved to form flanges 2 engaged by a locking strip 3 and which is removable therefrom to permit the drum or fire box to be disassembled when desired. 55

The drum 1 is mounted upon a base 4 consisting of a substantially rectangular shaped frame 5 having formed upon its upper edges inwardly extending and overlapped supporting flanges 6. The flanges 6 are cut away as shown at 7 to form notches adapted to receive the companion flange thereto. A circular plate 8 is detachably secured to the flanges 6 by bolts or like fasteners 9 and forms the bottom wall of the fire box of the drum and has secured thereto a cylindrical portion 10 which receives the lower end of the fire 70 box or drum and has tight frictional contact therewith. The frame 4 is provided with a plurality of openings 11 to permit free circulation of air under the fire box or drum to permit the heat to escape and to maintain 75 the frame comparatively cool so as not to injure the floor or support on which the frame may be positioned.

A cover 12 is removably mounted on the upper end of the fire box or drum and has a cylindrical portion 13 which frictionally engages the drum or fire box to prevent accidental displacement of the cover or the escape of flames or products of combustion 80 from the upper end of the stove. The cover 12 is provided with a fuel opening 14 surrounded by a neck 15 forming an integral part of the cover and normally closed by a lid 16. The lid 16 is secured to the cover 12 by a hinge 17 and is also provided with a finger piece 18 to permit the lid to be opened 85 and closed for the purpose of placing fuel into the fire box or drum and to remove ashes therefrom. 90

The cover 12 is provided with an oval 95 shaped opening 19 surrounded by a flange 20 to be engaged by the usual smoke stack 21. The cover 12 is provided with an opening 21' to receive a tube 23, the lower end of which is cut away to form an extension 24. 100

adapted to rest upon the surface of the ashes 25 within the fire box or drum, thus providing an efficient draft to the fire burning upon the ashes. The tube is slideable relative to 5 the cover so that it may adjust itself according to the amount of ashes within the drum or fire box. A rod 26 which may be used as a poker extends into the tube and has journalled thereon a disk or plate 27 adapted to 10 form a damper or regulator for controlling the draft through the tube. The rod 26 is provided with a handle 28 to permit said rod to be easily employed as a poker for agitating the fire and also forms a support in 15 connection with the plate 27 in supporting the rod within the tube 23.

While I have shown and described the preferred embodiment of my invention, it will be understood that minor changes in construction, combination and arrangement of 20 parts may be made without departing from the spirit and scope of my invention, as claimed.

Having thus described my invention, what 25 I claim is:

A stove comprising a frame having openings to permit air to circulate therethrough, overlapping horizontal supporting flanges on the upper edges of the frame, a circular 30 shaped plate resting on and detachably secured to said flanges, an annular upstanding flange on said plate, a cylindrical drum having one end resting on the plate and frictionally gripped by said annular flange to co- 35 operate with the plate in forming a fire box, and a cover removably mounted on the upper end of the drum and having an exhaust opening to receive a smoke pipe.

In testimony whereof I affix my signature.

TELESPHORE BABIN.
